FLORAL MEMORIAL MARKER

John Gialoreta, 1514 E. 96th St., Brooklyn, N.Y.

Filed Jan. 17, 1961, Ser. No. 63,580

Term of patent 7 years

(Cl. D79—2)

FIG. 1.

FIG. 4.

FIG. 1 is a front elevational view of a floral memorial marker showing my new design with the legs broken off for convenience of illustration; and

FIGS. 2, 3 and 4 are top plan, rear elevational and left side elevational views, respectively thereof.

The side not illustrated is substantially identical to that shown in the drawings.

The dominant features of my design reside in the portions shown in full lines.

I claim:

The ornamental design for a floral memorial marker, substantially as shown, and described.
